UNITED STATES PATENT OFFICE

WILLIAM H. CAPE, OF CUMBERLAND MILLS, MAINE, ASSIGNEE TO S. D. WARREN COMPANY, OF BOSTON, MASSACHUSETTS, A CORPORATION OF MASSACHUSETTS

PAPER MAKING APPARATUS

Application filed April 28, 1931. Serial No. 533,377.

This invention relates to the art of forming a web of paper or like material, and to means for controlling the fiber density and/or the thickness of the forming web. It is customary in the manufacture of paper to maintain a supply of paper stock at a level above that of the traveling surface such as the wire of a Fourdrinier machine onto which the stock is to be delivered so that the head thus provided may be utilized for causing the stock to flow onto the wire. In order to form a web one or more slice bars or the like may be arranged to extend transversely above the wire in spaced relation thereto. The slice bars function as an obstruction to hold back a pond of paper making stock between the flow box and the wire, the head thus provided being utilized to cause the stock to issue from beneath the bars with a velocity corresponding to that of the traveling wire. These slice bars also cooperate with the traveling surface or wire to limit the thickness of the forming web as it passes beneath the bars. In machines used for manufacturing only one width of web, each slice bar may be a single or non-composite member of fixed length, but frequently these bars are adjustable or extensible longitudinally to be adaptable for use in forming webs of different widths. Under normal operating conditions it not infrequently happens that eddy currents or other disturbances are produced in the flow box or pond which cause irregularities in flow or delivery of the stock. These conditions of flow are not effectively controlled by slice bars of the usual construction and thus often result in the formation of a sheet of material of variable thickness or fiber density across the web.

Objects of the present invention are to improve the art of forming webs of the class referred to so as to overcome the undesirable conditions resulting from unequal or irregular flow and thus to provide for forming a web of substantially uniform thickness and fiber density; to provide improved means for controlling the thickness and/or fiber density of the forming web; to provide apparatus for these purposes of relatively simple and efficient and yet strong and durable construction; and also to provide appa-

ratus of the class described having an improved construction and relative arrangement of parts.

In the drawings:

Fig. 1 is a side elevation of the wet end of a Fourdrinier machine with parts omitted and broken away;

Fig. 2 is a plan view of a portion of the apparatus shown in Fig. 1;

Fig. 3 is a section along the line 3—3 of Fig. 2;

Fig. 4 is a section along the line 4—4 of Fig. 2;

Fig. 5 is a plan view, to an enlarged scale, showing the adjoining ends of the sections comprising the slice shown in Fig. 4.

Fig. 6 is a section along the line 6—6 of Fig. 5; and

Fig. 7 is a side elevation of a portion of the slice shown in Fig. 5.

The features of the invention are illustrated in the drawings as embodied in a Fourdrinier machine comprising a framework indicated generally at 10 which supports the breast roll 11 and a series of table rolls 12. The traveling surface or wire 13 is trained over the breast roll 12, the upper run of this wire passing above and being supported by the table rolls 12. A flow box 14 is disposed adjacent the breast roll for delivering paper stock to the traveling wire. At each side of the machine rails 16 and 17 extend longitudinally of the traveling wire and carry brackets 18 and 19 which rotatably support transversely disposed bars 20. These bars are threaded oppositely from the ends thereof and each of these threaded portions carries hangers or brackets 21 and 22 respectively each having a smooth bore which slides freely over the threads. The deckle frames 23 and 24 are supported by the brackets 21 and 22. At each side of the machine shafts 26 are mounted upon the deckle frames and carry worm wheels 27 in enmeshment with the threads of the bars 20 so that these shafts may be rotated to move the deckle frames relatively toward and from each other. The deckle apparatus (not shown) is mounted upon these deckle frames in the usual manner.

In the form of apparatus shown two slices or slice bars 28 and 29 are arranged to extend transversely across the traveling wire between the deckle frames. These slices are 5 of the extensible type and comprise sections 31 and 32 which overlap at the center and are secured in the desired position of adjustment longitudinally with respect to each other by clamping members 33 and 33'. As 10 shown more clearly in Figs. 4 to 7, each section may comprise a vertically disposed flat plate having a reinforcing flange 34 or 35 extending longitudinally along the top edge thereof. The clamping members 33 are in 15 the form of U-shaped clamps which embrace the reinforcing flanges 34 or 35. The clamping members are fixed alternately to the members 31 and 32. One end of each clamping member, as the end 37 of member 33 is 20 fixed to the one section while the other end of this clamping member carries an adjusting screw 38 which is adapted to hold a clamping element 39 against the adjacent section and thus firmly to clamp the two sections together. Each clamping member may 25 also be fitted with a vertically disposed adjusting screw 41 arranged to engage one of the upper flanges, as the flange 35 of the section 32 for raising or lowering the central portion of the slice or if desired for adjusting the two sections of the slice in longitudinal alignment.

In accordance with the present invention the adjacent sides of each of the sections 31 35 and 32 are fitted with facing plates 42 and 43. These may be relatively thin plates which extend above and below the sections associated therewith and have along their upper edges outwardly disposed flanges 44 40 and 46. The plates 43 associated with the section 32 carry headed pins or rivets 47, 48 and 49, the shanks of these rivets being slidably received in vertically disposed slots 47', 48' and 49' with the heads overlying 45 these slots so as effectively to retain the facing plates on the section. It will be understood that the facing plates 42 are mounted upon the section 31 in a like manner. The upper flange of each facing plate overlies 50 the upper flange of the associated section. An adjusting screw 51 extends between these flanges and has threaded engagement with the lower flange 34 and is freely slidable through an enlarged opening or slot 42 in 55 the flange 44 of the facing plate. This adjusting screw preferably is mounted directly above the retaining pin 48 and its associated slot 48'. At the ends of each facing plate adjusting screws 53 and 54 are threaded 60 through the flange of the plate to bear upon the flange 35 of the section 32 or upon the flange 34 of the section 31. The adjusting screws 53 and 54 are arranged directly above the pins 47 and 49 respectively. The 65 adjoining marginal portions or ends of the

facing plates associated with each section are cut away or rabbeted as indicated clearly at 56 in Fig. 5 so that these sections may overlap and may be capable of tilting movement or relative vertical adjustment without leaving steps or other projections along the lower edge of the plates. The sections 31 and 32 of each slice are supported from the deckle frames and arranged to slide vertically in slotted bosses 57 and 58 carried by 70 the deckle frames. 75

In using this apparatus the paper making machine is operated in the usual manner, paper stock being delivered from the flow box onto the traveling wire at the breast roll is held back by the slice bars and issues beneath the latter in a thin stream traveling at the velocity of the wire. As conditions are observed which give rise to eddy currents or other irregularities in flow of the stock, such as ordinarily result in the formation of a web of non-uniform fiber density or variable thickness, the facing plates may be adjusted vertically to correct such conditions. For instance, these plates may be adjusted independently by loosening the screws 53 and 54 and operating the screw 51 to raise or lower the plate while the end screws 53 and 54 may be employed for tilting or canting the plate about the rivet 48, and at the same time securing the plate vertically in position. It will also be seen that instead of adjusting each plate individually the entire series or at least a plurality of plates may be adjusted so as to arrange their lower edges in a straight 100 or curved line as conditions may require. In this way, it is possible to overcome the defects of improper flow or delivery of the stock so as to assure even distribution and the formation of a sheet of paper of uniform fiber 105 density across the web and also of uniform thickness. While both slices have been shown as equipped with facing plates in accordance with this invention, it will be understood that in many cases, only one of 110 these slices need be so equipped, and in fact it has been found that very satisfactory results may be obtained by providing these facing plates only on the second slice, that is the 115 one adjacent the dry end of the machine.

It should be understood that the present disclosure is for the purpose of illustration only and that this invention includes all modifications and equivalents which fall within the scope of the appended claims. 120

I claim:

1. In an apparatus for forming a traveling web of paper stock comprising a traveling surface and an extensible slice bar comprising sections movable longitudinally relative to each other and disposed transversely across the travelling surface, the combination of means disposed along adjacent sides of said sections and independently adjustable relative to the travelling surface at points 125 130

spaced along the slice bar for maintaining the forming web of a substantially uniform thickness transversely thereof.

2. In an apparatus for forming a travelling web of paper stock comprising a travelling surface and an extensible slice bar comprising sections adjustable longitudinally relative to each other and disposed transversely across the travelling surface, the combination of means carried on adjacent sides of the sections and independently adjustable relative to the travelling surface at points spaced along the slice bar for maintaining the travelling web of a substantially uniform thickness transversely thereof.

3. In an apparatus for forming a travelling web of paper stock comprising a travelling surface and a slice bar disposed transversely thereacross, the combination of a plurality of plates disposed in overlapping relation along the slice bar, and means for supporting the plates for individual adjustment transversely of the slice bar and relative to the travelling surface, whereby the forming web may be maintained at a substantially uniform thickness thereacross.

4. In an apparatus for forming a travelling web of paper stock comprising a travelling surface and a slice bar disposed transversely thereacross, the combination of a plurality of plates disposed in overlapping relation along the slice bar, and means for supporting the plates for individual adjustment relative to the travelling surface and transversely of the slice bar about pivotal axes spaced therealong, whereby the forming web may be maintained at a substantially uniform thickness thereacross.

5. In an apparatus for forming a travelling web of paper stock comprising a travelling surface and a slice bar disposed transversely thereacross, the combination of a plurality of facing plates disposed along the slice bar, headed pins mounted on one of the latter members and extending through slotted openings in the other thereof for retaining the plates on the bar, and means for adjusting the plates individually relative to the travelling surface, whereby the forming web may be maintained at a substantially uniform thickness thereacross.

6. In an apparatus for forming a travelling web of paper stock comprising a travelling surface and a slice bar disposed transversely thereacross, the combination of a plurality of facing plates disposed along the slice bar, headed pins mounted on one of the latter members and extending through slotted openings in the other thereof for retaining the plates on the bar, means associated with each plate and disposed above one of the pins cooperating therewith for raising the plate, and other means disposed above another of the pins cooperating with each plate for lowering the latter, whereby the

lower edge of each plate may be adjusted to project below the bar at different inclinations.

7. In an apparatus for forming a travelling web of paper stock comprising a travelling surface and a slice bar disposed transversely thereacross, the combination of a plurality of facing plates disposed along the slice bar, means for adjusting each plate relative to the travelling surface comprising a plurality of adjusting screws associated with each plate and spaced longitudinally along the bar, at least one of the screws for each plate being adapted to lower the same while another of the latter screws is adapted to raise the plate, whereby each plate may be canted so that its lower edge is disposed at different inclinations.

8. In an apparatus of the class described, the combination of a slice bar, a plurality of plates disposed along the slice bar and adapted to project below the latter, means for retaining said plates on the slice bar and for supporting said plates for substantially vertical movement relative to each other and relative to the slice bar, and means for securing said plates in desired positions of adjustment so that the lower edges of said plates may be arranged to project below the slice bar to control the flow of paper stock.

9. In an apparatus of the class described the combination of a slice bar and means providing a locally adjustable lower edge adapted to project below the slice bar for controlling the flow of paper stock thereunder, said means comprising a plurality of members having lower edge portions disposed along the slice bar substantially in end to end relation to form said locally adjustable lower edge, means for supporting said members along the slice bar for individual adjustment, and means for securing said members in different positions of adjustment.

10. In an apparatus of the class described the combination of a slice bar and means providing a locally adjustable lower edge adapted to project below the slice bar for controlling the flow of paper stock thereunder, said means comprising a plurality of members having lower edge portions disposed along the slice bar substantially in end to end overlapping relation to form a substantially continuous lower edge, means for supporting said members along the slice bar for individual vertical adjustment relative to each other and relative to the slice bar, and means for securing said members in different positions of adjustment, whereby said substantially continuous lower edge may be maintained in the desired position of adjustment.

11. In an apparatus of the class described the combination of an extensible slice bar comprising overlapping sections adapted to be secured in different positions of adjustment longitudinally of each other, and means providing a locally adjustable lower edge

- adapted to project below the slice bar for controlling the flow of paper stock thereunder, said means comprising a plurality of plate members having lower edge portions disposed along the slice bar substantially in end to end relation to form said locally adjustable lower edge, at least two of said plate members being disposed in side by side relation between the overlapping portions of said sections of the slice bar, means for supporting said plate members for individual adjustment relative to each other, and means for securing said plate members in different positions of adjustment.
12. In an apparatus of the class described the combination of an extensible slice bar comprising overlapping sections adapted to be secured in different positions of adjustment longitudinally of each other, and means providing a locally adjustable lower edge adapted to project below the slice bar for controlling the flow of paper stock thereunder, said means comprising a plurality of plate members having lower edge portions disposed along the slice bar substantially in end to end relation to form said locally adjustable lower edge, said plate members being disposed along the slice bar on the adjacent sides of said sections substantially from the outer ends thereof to a position between the overlapping portions of said sections, at least two of said plate members being disposed in side by side overlapping relation between the overlapping portions of said sections of the slice bar, means for supporting said plate members for individual adjustment relative to each other, and means for securing said plate members in different positions of adjustment.
13. In an apparatus of the class described the combination of an extensible slice bar comprising overlapping sections adapted to be secured in different positions of adjustment longitudinally of each other, and means providing a locally adjustable lower edge adapted to project below the slice bar for controlling the flow of paper stock thereunder, said means comprising a plurality of plate members having lower edge portions disposed along the slice bar substantially in end to end relation to form said locally adjustable lower edge, at least two of said plate members being disposed in side by side relation between the overlapping portions of said sections of the slice bar, means for supporting said plate members for individual adjustment relative to each other, means for securing said plate members in different positions of adjustment, and means for clamping the overlapping portions of said sections and the interposed plate members together to secure said sections in the desired position of adjustment relative to each other.
14. In an apparatus of the class described the combination of an extensible slice bar comprising overlapping sections adapted to be secured in different positions of adjustment longitudinally of each other, and means providing a locally adjustable lower edge adapted to project below the slice bar for controlling the flow of paper stock thereunder, said means comprising a plurality of plate members having lower edge portions disposed along the slice bar substantially in end to end relation to form said locally adjustable lower edge, some of said plate members being disposed along each of the sections of the slice bar and on adjacent sides of said sections, means carried by each of said sections for supporting the plate members associated therewith for individual adjustment relative to each other, means for securing the plate members in desired positions of adjustment, at least one of the plate members associated with each of said sections being disposed between the overlapping portions thereof.
15. In an apparatus of the class described the combination of an extensible slice bar comprising overlapping sections adapted to be secured in different positions of adjustment longitudinally of each other, and means providing a locally adjustable lower edge adapted to project below the slice bar for controlling the flow of paper stock thereunder, said means comprising a plurality of plate members having lower edge portions disposed along the slice bar substantially in end to end relation to form said locally adjustable lower edge, some of said plate members being disposed along each of the sections of the slice bar and on adjacent sides thereof, means for supporting the plate members for individual adjustment, at least one of the plate members associated with each section being disposed substantially between the overlapping portions thereof, the faces of the plate members which are disposed outwardly from the section with which they are associated being smooth and free from projections to provide for sliding engagement of these faces of the plate members of both sections to effect longitudinal adjustment of said sections.
- Signed by me at Cumberland Mills, Me., this eighteenth day of March 1931.
